UNITED STATES PATENT OFFICE.

WICKES WASHBURN, OF ROSELLE, NEW JERSEY.

TOBACCO-SAVER.

1,210,877.

Specification of Letters Patent. Patented Jan. 2, 1917.

Application filed October 7, 1915. Serial No. 54,671.

To all whom it may concern:

Be it known that I, WICKES WASHBURN, a citizen of the United States, residing at Roselle, in the county of Union, State of New Jersey, have invented a certain new and useful Improvement in Tobacco-Savers, of which improvement the following is a specification.

This invention relates to devices adapted to be attached to a bag for feeding tobacco or similar substances therefrom, and for closing the bag when not in use.

With the ordinary tobacco bag having strings adapted to be drawn together to close the same, when tobacco is being emptied or shaken therefrom into a pipe or a paper for the purpose of making a cigarette, a considerable amount of the tobacco is usually spilled and wasted, and the object of my invention is to provide a feed tube device and closure which may be readily attached to the ordinary tobacco bag, and be easily and conveniently operated to deliver tobacco from the bag into a cigarette paper or pipe without spilling, and then be instantly closed when desired.

In the accompanying drawing: Figure 1 is a vertical section of a device embodying my improvement, and showing the same applied to a bag; Fig. 2, a side elevation; and, Fig. 3, a horizontal section taken on the lines 3—3 of Fig. 1.

According to the preferred form of the improvement as shown in the drawing, the construction comprises a short outer tube, 3, having a flange, 4, at its lower end over which the mouth of the bag may be fastened in any convenient manner, and a longer inner tube, 5, telescoping within the outer tube, and mounted to have longitudinal and rotatable movements therein. The outer end of the inner tube, 5, is provided with a closing cap, 6, and lateral openings, 7, which may be drawn out beyond the end of the outer tube when it is desired to open the feed tube for the discharge of a certain amount of the tobacco. When the inner tube is pushed inward, the cap, 6, engages the outer end of the outer tube, preventing further inward movement, and effectually closing the discharge opening from the tube, as shown in Fig. 2.

The lower end of the inner tube is provided with one or more laterally extending or curved blades or projections, 8, which are adapted, upon rotation of the inner tube, to

loosen up the tobacco or other substance and allow the same to freely enter the inner tube. These projections also limit the outward movement of the inner tube to the desired point at which the lateral ports are fully open. The flange, 4, at the inner end of the outer tube serves also to hold the bag away from the rotatable blades, thereby preventing the blades from catching the sides of the bag, and also avoids tearing or injury thereto.

As a convenient means for fastening the bag upon the outer tube above the flange, 4, I have shown a clamping ring, 9, mounted to turn and slide upon the outer tube, and having notches for passing the lugs, 10, rigidly secured upon the outer tube near the flange, 4. The mouth of the bag may then be pulled over the flange of the outer tube and the clamping ring, 9, then slipped down past the lugs and turned to clamp the bag between said ring and the said flange or plate. The clamping ring may obviously be threaded upon the outer tube, if preferred.

When it is desired to take out a certain amount of tobacco for filling a cigarette paper or pipe, the inner tube is pulled out by means of the cap, to open the lateral openings, and at the same time may be turned to loosen up the particles of tobacco within the bag. As the bag is then turned at the proper angle, the tobacco flows freely through the inner tube, and is discharged through one of the lateral openings at the outer end directly to the point desired. After a sufficient quantity is discharged, the tube may be instantly closed by pushing in the inner tube, and all spilling and waste of the tobacco is thereby avoided.

Having now described my invention, what I claim as new, and desire to secure by Letters Patent is:

1. The combination of an outer tube having a flange at its lower end, means for detachably securing a bag thereto over said flange, an inner tube rotatably mounted within the outer tube and having lateral discharge openings, stirring means secured to said inner tube below said flange, and a cap closing the outer end of said tube.

2. The combination of an outer tube having a flange at its lower end, means for detachably securing a bag thereto over said flange, an inner tube mounted to rotate and reciprocate within said outer tube and having lateral discharge openings at its outer

end, stirring blades extending laterally from the end of the inner tube below said flange, and a cap secured to the outer end of the inner tube and seating against the end of the outer tube in closed position.

3. The combination of an outer tube having a flange at its lower end, means for detachably securing a bag thereto over said flange, an inner tube mounted to rotate and

reciprocate within said outer tube and having lateral discharge openings at its outer end, stirring means secured to the lower end of the inner tube below said flange, and a cap for closing the outer end of the tubes.

WICKES WASHBURN.
